[57] CLAIM

The ornamental design for a rear view mirror assembly
for a pickup truck, or similar article, as shown.

DESCRIPTION

FIG. 1 is a front elevational view of a rear view mirror
assembly for a pickup truck, or a similar article, showing
my new design;

FIG. 2 is a right side elevational view of FIG. 1;

FIG. 3 is a left side elevational view of FIG. 1;

FIG. 4 is a rear elevational view thereof;

FIG. 5 is a top plan view of FIG. 4;

FIG. 6 is a bottom plan view of FIG. 1.
